UNITED STATES PATENT OFFICE.

BARTHolemew S. WILLIAMS, OF AURORA, MISSOURI.

REFRIGERATOR.

SPECIFICATION forming part of Letters Patent No. 612,983, dated October 25, 1898.

Application filed December 16, 1897. Serial No. 662,126. (No model.)

To all whom it may concern:

Be it known that I, BARTHolemew S. WILLIAMS, a citizen of the United States, residing at Aurora, in the county of Lawrence and State of Missouri, have invented certain new and useful Improvements in Refrigerators; and I do declare the following to be a full, clear, and exact description of the invention, such as will enable others skilled in the art to which it appertains to make and use the same.

My invention has relation to a refrigerator or ice-box; and the object is to simplify the construction and provide a compact and convenient device of this character capable of containing many and large varieties of edibles separated from one another and yet be intimately associated with the cold air of the refrigerator.

With this object in view the invention consists in certain features of construction and combination of parts, which will be herein-after fully described and claimed.

In the accompanying drawings, Figure 1 is a perspective view of my improved refrigerator, and Fig. 2 is a detail perspective view of the ice tray or receptacle.

In said drawings, 1 denotes the frame of the refrigerator, which is preferably rectangular in form and is provided with a door 1^a. Within this casing are placed two concentric casings 2 and 3, provided with doors 2^a and 3^a, respectively. These concentric casings are spaced apart and are provided with supporting-legs 4.

5 5 denotes the ice tray or receptacle, the sides of which are preferably recessed, as shown at 6, which, in connection with the adjacent walls of the box, form compartments for bottles or similar articles, while the spaces

above and below form provision-chambers. 40 This receptacle is provided on its top with a sliding cover 8, enlarged to permit of the insertion of ice.

A refrigerator thus constructed has a large storing capacity and may be easily cleaned 45 by simply withdrawing the inner concentric casings and the ice-receptacle. In the present instance the ice-receptacle is shown as being supported within the innermost casing by brackets 9, secured to the sides of said 50 casing. Other means, however, may be substituted without affecting the invention.

Although I have specifically described the construction and relative arrangement of the several elements of my invention, I do not 55 desire to be confined to the same, as such changes or modifications may be made as clearly fall within the scope of my invention without departing from the spirit thereof.

Having thus described my invention, what 60 I claim, and desire to secure by Letters Patent, is—

The combination in a refrigerator of a box or casing and the horizontally-removable ice-receptacle fitting the side walls thereof and 65 supported therein so as to form provision-spaces above and below the same, the sides of the ice-receptacle having recesses or depressions forming with the adjacent walls of the box, compartments for bottles or similar 70 articles, substantially as described.

In testimony whereof I hereunto affix my signature in presence of two witnesses.

BARTHolemew S. WILLIAMS.
